UNITED STATES PATENT OFFICE.

CLINTON L. BELL, OF DECATUR, ILLINOIS.

HASP LOCK.

Application filed December 20, 1920. Serial No. 431,357.

To all whom it may concern:

Be it known that I, CLINTON L. BELL, a citizen of the United States, a resident of Decatur, in the county of Macon and State 5 of Illinois, have invented new and useful Improvements in Hasp Locks, of which the following is a specification.

This invention has reference to new and useful improvements in hasp-locks, and it 10 has for its principal object to provide a hasp-lock which is attachable to and useful on doors which swing or which slide, and reversible for right or left.

The invention has for a further object to 15 provide a hasp-lock for sliding or swinging doors, including latching means which will automatically lock the door closed, and arranged to be released from the inside as well as the outside of the door. The hasp-plate 20 and keeper plate being arranged to receive a pad-lock when it is desired to employ other and permanent locking means to the latching means.

A further object of the invention is to 25 make the several elements of the lock from stamped metal, which insures a more rigid and lasting construction and provides a lock of the character referred to which may be manufactured at very low cost.

With the above and other objects in view, 30 my invention comprises certain new and useful details of construction and arrangement of parts which will be fully described herein, illustrated in the accompanying drawings, 35 and pointed out more specifically in the appended claims.

In describing my invention in detail, reference will be had to the accompanying drawings, illustrating a preferred embodiment 40 of the invention, wherein like characters denote like or corresponding parts throughout the several views.

In the drawings:—

Fig. 1 is a front elevation of my improved 45 hasp-lock, the hasp plate and keeper plate being separated to show them in unattached relation;

Fig. 2 is a view similar to Fig. 1, except 50 the parts are in locked relation, the position they would be in when the door is closed;

Fig. 3 is a cross-section as the same would appear if taken on the line 3—3 of Fig. 2;

Fig. 4 is a longitudinal section view of the parts as the same would appear when in 55 the position shown in Fig. 2, and

Fig. 5 is a cross-section as the same would

appear if taken on the line 5—5 of Fig. 4.

A designates what may be termed a swinging or a sliding door of a barn or outbuilding, and B the door jam. I am not concerned 60 as to the character of the swinging or sliding door, as the lock is constructed for adaptation to either type and will accommodate itself to either and the parts guided to locking position even though the door may have 65 sagged some. Further, the latching parts are protected against the weather so as to prevent rusting, and they are arranged to be operated from the inside as well as the outside of the door, and so guarded as to prevent 70 the unlatching thereof by horses or other animals.

1 designates the hasp-plate and 2 the keeper plate. The plate 1 is preferably bolted to the door A by bolts 3, 4 and 5, each of 75 which pass through slots 6 in said hasp plate to allow for adjustment and regulation of the hasp plate on the door. The bolts 4 and 5 also serve to secure a cover plate 7 to the inside face of the door A, and said 80 plate has an opening 8 for the insertion of the fingers therethrough and into an opening 9 through the door, into which projects a pin 10, which also projects through a slot 11 in the hasp plate 1, and connected in a manner 85 to be described with a latch member 12. The plate 2 is preferably attached to the door jam B by means of the screws 13.

The hasp plate 1 and the keeper plate 2 are preferably stamped metal parts. The 90 plate 1 comprising a long narrow rectangular strip which is secured to the door with a part thereof projecting beyond the front edge thereof, and the end of such projected portion is wedge shape, as at 14, and such 95 wedge portion is bent outwardly at a suitable inclination from the main body of the plate, as shown. Said wedge portion is provided with an opening 15 therethrough.

The keeper plate 2 is formed with the flat 100 body portion 16, the upper and lower edges of which are formed with outwardly bent flanges 17 which converge from the edge of the plate coincident with the edge of the door jam to the main body of said plate, 105 or to a point where said plate is bent outwardly at a suitable inclination, as at 18, being similar to the portion 14 of the hasp plate, the edges of said inclined portion 18 of said keeper plate being turned inwardly 110 toward the jam, as at 19 providing a brace when the hasp plate and keeper plate are

forcibly brought together, and also forming a shed over which harness from a horse may slip in the event of any harness catching thereon as the horse goes into the barn, and thereby prevent breaking of the harness or stripping off of the keeper plate. The inclined portion 18 of said keeper plate has an opening 20 therethrough, with which the opening 15 of the hasp plate will coincide when the door A is closed, and a padlock C, dotted lines Fig. 4 may be passed through both said plates for the purpose of affording a more permanent lock for the hasp, should it be desired to use such a lock at any time. The flat body portion 16 of the keeper plate 2 overlies a recess 21 in the jam which, as shown, opens out of the edge of said jam, and the plate 2 has a slot 22 cut therein from the edge of said plate. The upper and lower edges of said slot are preferably beveled, as at 23 for a portion of their length, terminating in shouldered seat 24. Said shouldered seats are preferably at the narrow end of said slot, the beveled edges 23 serving to guide a latch to the shouldered seats. The formation of the keeper plate is such that it is possible to use it right or left, and in either case only the lower shouldered seat 24 receives the latch member. I prefer to provide a guard plate 25 for the upper beveled edge 23 and upper shouldered seat 24, the same being secured in place by one of the screws 13, see Fig. 1. The function of the guard plate 25 will be more fully explained.

The latch member 12 is also preferably a stamped plate and is formed with flanges 26 which are bent back against each other to provide a rib 27 extending laterally from the body of the latch to provide an engaging means by which the latch may be manipulated from the outside of the door. The pin 10 previously referred to, by means of which the latch may be manipulated from the inside of the door is first passed through an opening in the main body of the latch, between the flanges 26, when they are bent back to form the rib 27, in the manner seen in Fig. 3, which will also serve to secure the pin to the said latch member. The member 12 has a pivotal connection at 28, at one end, to the plate 1 and its forward or operating end has a transverse slot 29 therethrough which may move up and down on a pin 30 secured to the plate 1, permitting a limited up and down oscillatory movement of said latch member. The end of the latch member is bent inwardly at right angles and is formed with the preferably arrow shaped head 31 at the end of a reduced neck portion 32. The head and neck providing shoulders 33. The bent end of the latch being preferably embossed, as at 34 to lend the necessary strength to the latch to meet the end thrust, if any, particularly when

the lock is used on a sliding door. The head 31 of the latch operates in a vertically disposed slot 35 in the plate 1 and when the plate 1 and plate 2 are brought into engaging relation, said head also operates in the slot 22 in the plate 2.

36 designates an open bottom housing preferably secured by screws 37 to the hasp plate 1, in a manner, as shown, to cover the latch 12 and protect it against snow and sleet and also to provide a pull for the hasp and the door.

Normally the latch 12 assumes the position shown in Figs. 1 and 2 with the pin 30 in the upper end of the slot 29 in the latch member 12, into which position the latch member will ordinarily gravitate. Assuming now that the device is attached to a sliding door, as the door is moved to a closed position against the jam the wedge shaped end 14 of the plate 1 is guided to position on the plate 2 by means of the converging flanges 17 on said plate 2; the head 31 of the latch entering the opening or recess 21 in the jam and the slot 22 in said plate 2, the neck 32 of the head of the latch riding up over the lower beveled edge 23 of the wall of the slot 22 until it drops into the shouldered seat 24 which will hold the member 12 against endwise movement until the latch has been lifted, either by engagement with the rib 27 on the outside, or by engagement with the pin 10 through the opening 9 in the door from the inside. Assuming that the device is attached to a swinging door, as the door reaches its closed position the wedge shaped end of said plate 1 will seat itself between the flanges 17 on the plate 2 and the beveled or arrow shaped end 31 of the latch will ride up and over the lowered shouldered seat 24 in the slot 23 in plate 2 until the shoulder 33 will engage back of the shoulder 24 to automatically lock the parts in closed position, from which position the latch may be removed in the same manner described for unlatching on a sliding door.

Referring now to the guard plate 25, this plate will prevent accidental engagement of the head 31 of the member 12 with the upper shouldered seat 24 on the plate 2, when the door is closed, momentarily holding the door closed, and leading the person who closed the door to believe it had latched, when upon leaving the door the latch might drop and at the same time the door be pushed or blown open letting stock or other animals escape from the building. The guard will prevent such mistakes occurring.

While I have made reference to the function of the slots 6 for adjustment and regulation of the hasp plate on the door, it is also understood that the slots allow for the sagging of the door, in case it should sag. While it is here shown possible to take care of any

sagging of the door, sagging, will not interfere with the free action of the latch, and it is possible in the event of sagging for some of the weight of the door to find support 5 by the resting of the lower edge of the hasp, plate 1, on the lower flange 17, of the plate 2.

In view of the fact that the screws 13, holding the plate 2, are covered by the plate when the door is closed, and the nuts for 10 the bolts, 3, 4, and 5, are on the inside of the door, when the padlock C is used, there is little possibility that ingress could be made to the building without cutting away some of the metal parts.

15 Attention is also called to the fact that the lower edge of the housing is flared or bell shaped, which not only increases the strength of the housing, but makes it more convenient to open with a glove or mitten on the 20 hand.

What I claim is:—

1. In a lock of the character described, in combination, a hasp plate attachable to a sliding or a swinging door, a keeper plate 25 attachable to a door jam, means on the keeper plate to seat the hasp plate thereon when the door is closed, and a latch member pivoted to said hasp plate and having an engaging end for a locking relation with said 30 keeper plate when sliding or swinging into engagement therewith.

2. In a lock of the character described, in combination, a hasp plate attachable to a sliding or a swinging door and having a 35 wedge shaped angularly bent end with an opening therethrough, a keeper plate attachable to a door jam and having an angularly bent portion to correspond with and receive the angular bent end of the hasp plate and 40 provided with an opening therethrough, such openings in said plates being for the reception of a key locking means, and a latch member pivoted to said hasp plate and having an engaging end for a locking relation 45 with said keeper plate when sliding or swinging into engagement therewith.

3. In a lock of the character described, in combination, a hasp plate attachable to a sliding or a swinging door and having a 50 wedge shaped angularly bent end with an opening therethrough, a keeper plate attachable to a door jam and having an angularly bent portion to correspond with and receive the angular bent end of the hasp plate 55 and provided with an opening therethrough, such openings in said plates being for the reception of a key locking means on the keeper plate to seat the hasp plate therein when the door is closed, and a latch member pivoted 60 to said hasp plate and having an engaging end for a locking relation with said keeper plate when sliding or swinging into engagement therewith.

4. In a lock of the character described, in 65 combination, a hasp plate attachable to a

sliding or a swinging door and provided with a slot, a keeper plate attachable to a door jam and provided with a slot having opposite beveled walls terminating in shouldered seats, and a latch member pivoted to said 70 hasp plate, said member having a shouldered and tapered head operating in the slot in said hasp plate and adapted to have a sliding or swinging engagement with the walls of the slot in said keeper plate to automatically 75 lock the door as it is closed.

5. In a lock of the character described, in combination, a hasp plate attachable to a sliding or a swingable door and provided with a slot, a keeper plate attachable to a 80 door jam and provided with a slot having opposite beveled walls terminating in shouldered seats, means on the keeper plate to seat the hasp plate thereon when the door is closed, a latch member pivoted to said hasp 85 plate and having an angularly bent head operating in the slot in said hasp plate, said head formed with a shoulder for locking relation with the walls of the slot in said keeper plate, engaging means permitting the 90 operation of said latch from the inside and the outside of the door, and an open bottom housing covering said latch member and serving as a pull for the door.

6. In a lock of the character described, in 95 combination, a hasp plate, a keeper plate having guiding means to seat the hasp plate thereon and also provided with a slot having a beveled wall terminating in a shouldered seat, a latch member pivoted to said hasp 100 plate and having a shouldered head arranged for a sliding relation with the beveled wall of the keeper plate slot and to latch the parts.

7. In a lock of the character described, in 105 combination, a hasp plate formed with a wedge shape slotted angularly bent end, a keeper plate formed with guiding means to seat the hasp plate thereon, and with a slotted angularly bent portion and a slot the 110 walls of which are beveled and terminate in shouldered seats, the slotted angularly bent portions of said plates adapted to receive a key locking means, a latch member formed with a rib and having a shouldered head for 115 locking engagement with the wall of the slot in said keeper plate, and a cover plate for said member.

8. In a lock of the character described, in combination, a hasp plate, a keeper plate 120 formed with upper and lower conveying flanges to guide and seat said hasp plate and provided with a slot having beveled walls terminating in shouldered seats, a guard plate to cover one of said beveled walls and 125 shouldered seats, and a pivoted latch member arranged for engagement with the walls of the slot in said keeper plate.

9. In a lock of the character described, in combination, a hasp plate attachable to a 130

door and having a pair of slots, a keeper plate attachable to a door jam having guiding means to seat the hasp plate and formed with a latch receiving slot, a latch member pivoted to said hasp plate and having flanges bent back against each other to provide an engaging rib, a pin secured to said member by the bending back of said flanges and adapted to lie within an opening through

the door, a head on said member for locking engagement with the wall of the slot in said keeper plate, means to limit the movement of said member, and an open bottom housing covering said latch member.

In witness whereof I have hereunto affixed my hand and seal this 14th day of December, 1920.

CLINTON L. BELL. [L.S.]
